UNITED STATES PATENT OFFICE.

HENRY E. TERRY, OF PHILADELPHIA, PENNSYLVANIA.

MACHINE FOR APPLYING REINFORCING MEANS TO RUG-SEAMS.

1,137,243.

Specification of Letters Patent. Patented Apr. 27, 1915.

Application filed October 6, 1914. Serial No. 865,303.

To all whom it may concern:

Be it known that I, HENRY E. TERRY, a citizen of the United States, and resident of Philadelphia, county of Philadelphia, and 5 State of Pennsylvania, have invented an Improvement in Machines for Applying Reinforcing Means to Rug-Seams, of which the following is a specification.

This invention relates to a machine for 10 applying a reinforcing means to the seam or seams of a rug or the like, in order to conceal the seam and prevent the same from opening up or stretching in the ordinary manner.

15 The invention has as an object to provide a machine for automatically feeding a seamed rug, carpet or the like, into operative relation with a reinforcing material or tape and automatically affixing such reinforcing means permanently to the seam or 20 seams, whereby the seams are permanently covered at the rear side of the rug.

It has for a further object to provide a means for softening and stretching the seams 25 of the article and also pressing the stretched seams preparatory to receiving the reinforcing material.

It has for a further object to provide an 30 indicating means for determining the proper alignment of certain adjuncts of the mechanism with the seam or seams so that the proper action takes place in the desired manner.

It has as a further object to provide a 35 means for applying a coating of adhesive material to one side of the reinforcing tape and automatically feeding such tape into juxtaposed position with respect to the seams of the article.

40 It has for a further object to provide a means for varying the position of the coated tape whereby its position with respect to the seam is presented with exactness.

It has for a further object to provide a 45 means for pressing the coated tape into position upon the seam and providing a means for drying the adhesive to permanently secure the tape to the article.

My invention also comprehends details of 50 construction which, together with the features above specified, will be better understood by reference to the drawings, in which:—

Figure 1 represents a plan of a rug-seam- 55 ing machine embodying my invention, certain portions of the machine being broken

away for clearness of illustration; Fig. 2 represents a sectional elevation on line 2—2 of Fig. 1; Fig. 3 represents a section on the line 3—3 of Fig. 2; Fig. 4 represents a section on line 4—4 of Fig. 1; Fig. 5 represents a section on line 5—5 of Fig. 1; Fig. 6 represents a side elevation, partly in section, of the adhesive applying mechanism; Fig. 7 represents a detail of the scraping mechanism used in conjunction with the adhesive applying means; Fig. 8 represents a section through one of the seams of the material showing the finished seam with the reinforcing material in place.

70 Similar numerals of reference indicate corresponding parts.

1 designates the main frame of the machine secured to which at the receiving end thereof is a plate or board 2 arranged in an 75 inclined position and serving to receive the material, cloth, rug, carpet or the like before it enters the machine. Adjacent this board 2 and normally resting upon the same there is a roll 3 carried by arms 4 and suitably hinged as shown at 5 to the frame 1 so that it may be raised or lifted in order to initially position the width of material upon the board 2. As soon as the material is 80 properly positioned the roll 3 is released and serves by its own weight as a means to keep the material free from wrinkles and in proper condition to enter the machine.

85 In the present instance the receiving board 2 terminates adjacent a conveying mechanism which is adapted to engage the material and feed it into proper relation to the operating adjuncts of the machine. As here shown, the conveyer mechanism consists of a pair of toothed conveyer belts 6 suitably 90 attached to the respective chains 7 which are driven by the sprocket wheels 8 and 9, the former pair of sprockets being carried by and fixed to the driven shaft 10 while the latter pair of sprockets is similarly connected to the driving shaft 10, this latter 95 receiving its motion from a chain and sprocket mechanism 11, driven from any suitable source of power.

100 12 designates a pair of rods fixedly secured to the frame 1 and preferably arranged in parallel relation to the shaft 10 for supporting the hangers 13 which carry the grooved guides 14. The grooved portions of the guides are adapted to receive 105 the teeth of the conveyer so that the material is firmly gripped during the feeding

operation. It will be obvious from Fig. 1 that the hangers 13 respectively support opposite end portions of the guides 14, the arrangement being such that the innermost end of each of the guides, as well as the adjacent conveyers, are spaced apart somewhat farther than the outermost ends of these parts. The object of this diverging relation of the conveyers is to initially stretch the material as it enters the machine so that the seams are stretched in a desired manner to bring the seams and the sections of the material into the same plane to eliminate the ridge generally formed by such a seam. The two conveyers 6 are driven from the sprockets 9 and move across the top or table 15 of the machine in a direction away from the inclined board 2, as will be understood.

20 In the present embodiment of my invention I have shown a machine adapted for use with a rug or carpet having four seams, but it will be noted that one of the supports for the conveyer frame 16 is removably attached to the cross frame 17 and may be shifted so that material of less width or less number of seams may be operated upon if desired. For this purpose the cross frame 17 is apertured at 18 to permit the conveyer frame to be bolted in the position desired.

19 designates a steam pipe extending transversely of the machine and suitably supported upon the machine for sliding movement with respect to the sides of the machine, the said pipe having connection to a suitable source of steam supply and exhausting at a suitable point by way of the pipe 20. This steam pipe 19 is provided at intervals with discharge openings 21 corresponding in number to the number of seams in the material, and each is located so as to discharge the steam directly against the adjacent seam. In view of the fact that the pipe 19 is below the top 15, the latter is apertured at a corresponding number of points as shown at 22 so that the steam may contact directly with the back of the material against the seam.

50 23 designates an arm attached to the steam pipe 21 and located above the table 15 so that the pointer 24, which is secured to said arm, may be positioned directly above the seam and thus determine the correct operative position of the steam discharge opening 21 with respect to the seams. Thus, for example, if the article enters the machine with the seam to one side of the pointer 24 it will be apparent that the steam outlet 21 will also be to one side of the seam rendering it ineffective for the purpose intended. It therefore becomes necessary to shift the arm until the pointer is directly aligned with the seam, thereby insuring the proper discharge of the steam.

The initial operation of feeding the rug or carpet to the machine, therefore, consists of placing the article upon the inclined board 2 beneath the roll 3, bringing it into position to be engaged by the toothed conveyer, feeding the article by means of these conveyers forwardly into the machine and simultaneously stretching it to bring the adjacent edges of the seam into the same plane and assisting this stretching operation by 75 heating the same with steam from the pipe 21. Following the foregoing operations the article is automatically engaged by another set of toothed conveyers 25, by which it is brought beneath the guide members 26 80 which maintain it in flat stretched condition while the seams are passing respectively through pairs of pressing rollers 27 and 28, the rollers 28 being rotatably mounted upon the shaft 10 while the rollers 27 85 are rotatably carried respectively by the frames 29 above the material, these latter being mounted for pivotal movement upon one of the rods 12 and held in operative position by the counterweight 30. As an additional feeding means I preferably provide a suitable number of toothed rollers 32 mounted to rotate with the shaft 10 and projecting through suitable openings in the table 15. In the present instance I have indicated but one set of seam-pressing rollers for engaging the material before the tape is supplied to the seam, but it will be understood that other sets may be employed if desired without departing from the spirit of 100 my invention.

After the stretched seam has been pressed by passing between the sets of rolls 27 and 28, it is ready for the application of the tape which is designed to protect the seam and hold it in its flat condition to prevent ridges being formed and also prevent the seam from opening up at the back of the article. The tape-applying means consists in the present instance of a plurality of spools of 110 tape 33, one spool for each seam of the cloth, and all of said spools being preferably mounted at the receiving end of the machine upon the spindle 34 as will be apparent.

115 In view of the fact that the tape-applying means as well as the treatment of the tapes by the adhesive is similar for each tape, the description will be limited to the mechanism for one tape, but will be understood as applying to all. 35 designates a tubular guide suitably fixed to the frame 1 and having one end positioned adjacent the spool 33 to receive the tape while its opposite end is located adjacent the adhesive applying means.

The adhesive applying means consists, in the present instance, of a receptacle or trough 36 suspended at opposite ends from the rods 37 which are fixed at one end to a 120

slidable block 38 and are suitably supported for sliding movement in the frame 1. The block 38 also carries a rotatable spindle 39 disposed between the rods 37 and carrying the applying roll 40 which is so positioned as to be partly submerged in the cement or adhesive 41. The cement or adhesive in the receptacle is kept in suitable viscous condition by means of a gas burner 42 located in operative relation to the receptacle 36. The tape 43, after leaving the guide 35, passes over a series of rolls 44 into contact with the roll 40 and thence to the device for pressing it to the material. The rolls 44 are mounted upon a frame 45 pivoted upon one of the rods 37 and is adapted to be moved from one position to another by means of the hand lever 46 which operates upon the proper rod 37. In normal operative position of the frame 45 the tape is maintained in contact with a portion of the periphery of the applying roll 40, as shown in Fig. 6, while in its inoperative position the frame is tilted to the dotted line position of Fig. 6 wherein the tape is removed from the said roll 40.

From the discharge end of the frame 45 the tape passes between the rolls 47 and 48, the former being rotatably mounted below the table but so positioned as to feed the tape through an opening 49 in the table and into contact with the seam of the material. The upper roll 48 is similar in construction and operation to the pressing rolls 27, and further description thereof is therefore deemed unnecessary.

The first pair of rolls 47 and 48 serve to press the tape into position across the seam of the material and after which the material passes across the face of a box 50 which has one surface projecting through the top 15 into contact with the cloth and is heated by steam from the supply pipes 51. In the preferred form of the invention I have shown a second pair of pressing rolls 51 and 52 at the other end of the drying box 50, and beyond these pressing rolls is a second drying box 50 so that after the tape is applied to the seam it is alternately pressed and dried as will be understood.

Referring again to the adhesive applying devices, it will be noted by reference to Figs. 1 and 3, that I have provided a means for adjusting the tape and the adhesive adjusting junctures transversely of the machine so as to insure the tape being properly aligned with respect to the moving seam. In this construction 53 designates an arm connected by the bar 54 with the block 38 and having at its outer free end the pointer 55 which serves to locate the exact position of the seam. The block 38 is provided with a rack 56 in mesh with the gear 57 which is fixedly supported on the frame 1 and rotated by means of the pinion 58 carried by the rod

59, this latter extending to a convenient point of operation where it terminates in the hand wheel 60.

It will thus be apparent by rotating the hand wheel 60 that motion will be transmitted to the rods 37 and 39 thereby shifting the tape, together with the applying mechanism, to one side of the other, whereby the tape is properly aligned with the seam. In connection with the rod 39 it will be noted by reference to Fig. 1 that it is rotatable and driven by means of a belt 61 from the driving shaft 10 and thus actuates the roll 40 to continuously bring a fresh supply of adhesive liquid into contact with the tape. 70 75 80

62 designates a scraper fixed to the frame 45 and so positioned as to normally contact with the tape to remove any excess of the adhesive, while its opposite end rests against the roll 40 and serves to prevent the adhesive drying and collecting upon the roll. 85

The main driving shaft 10 also transmits motion to the shaft 63 for the presser rolls 47 and to the shaft 64 for the presser rolls 51, through the medium of the driving chains 65 and 66, both of which operate about sprockets upon the shaft 10, as will be understood. A separate chain drive 67 is employed between the shaft 64 and shaft 68 to transmit movement from the former to the latter and thus operate the conveyors 25. 90 95

In the operation of the machine the rug or carpet, formed in sections joined by seams, is positioned upon the receiving board 2 beneath the roll 3 and has its end attached to the conveyors 6. These latter being in operation, feed the rug into engagement with the main conveyors 25 and at the same time stretch the rug laterally in a manner to 100 open up the seams to the extent of bringing the rug sections into the same plane and eliminating the ridge seam. This stretching action is materially assisted by the heated steam jets from the pipe 21 which 105 soften the seam so that it is more readily adapted to receive the reinforcing strip of tape which is to be applied. It will be understood that if the seams are not properly aligned with the steam jet openings 21, the 110 latter may be brought to proper operative position by sliding the pipe 21 transversely of the machine in the required direction until the pointer 24 indicates that the parts have reached proper operative position. After 115 the stretching action and as the rug is moved forwardly by the conveyor 25, the seams are respectively pressed by the rolls 27 preparatory to receiving the reinforcing tape. 120

When the rug reaches the rolls 47 and 48 125 it encounters the tape one side of which has been coated with the adhesive liquid. The action of the rolls 47 and 48 is to press the tape over the seam and closely bind the two materials together. This pressing and feed- 130

ing operation of the tape and rug take place simultaneously and continuously and the rug passes from these rolls to bring the 50 taped portions over the heating boxes 50 which initially dry the adhesive thus fastening the tape in fixed position. From these heating boxes the seams of the rug again pass through sets of pressing rolls and are then again subjected to the drying action 10 from the second set of heating boxes 50. The action, as will be noted, is one of alternately pressing and heating the taped seams so that when the rug finally leaves the machine the seam is effectively covered and re-inforced by a binding tape which is made 15 fast by the adhesive which is set during the drying and pressing operations. In Fig. 8 is shown a section through one of the rug seams wherein 69 designates the abutting 20 rug sections joined by the seam 70 which is reinforced and covered by the permanently attached tape 71. It will be noted that the seam ridge is entirely eliminated while any tendency of the seam to open up is effectively 25 prevented by the binding action of the tape.

Having now described my invention, what I claim and desire to secure by Letters Patent is:—

30 1. In a machine of the character stated, the combination of means for feeding an article having a plurality of parallel seams into and through the machine, a plurality of tape guides for feeding the tapes to the 35 seams of the article, means for applying paste to one side of the respective tapes, means for pressing the pasted tapes upon the respective seams of the article, and means for drying the respective tapes after leaving 40 the pressing means.

2. In a machine of the character stated, the combination of means for feeding an article forward and stretching it laterally to flatten its seams, and means for pressing a 45 pasted tape over and upon the stretched seam for covering the same and holding it in a flat condition.

3. In a machine of the character stated, the combination of means for feeding an 50 article forward and stretching it laterally to flatten its seams, means for pressing a pasted tape over and upon the stretched seam for covering the same and holding it in a flat condition, and drying means for drying 55 the pasted tape after it is applied.

4. In a machine of the character stated, the combination of means for feeding a seamed article into the machine and simultaneously stretching said article, a conveyor mechanism for receiving said article from the feeding means, means for applying and permanently securing a reinforcing material to said article for covering the seamed portion, and means adjacent the stretching

means for treating the seamed portions with steam.

5. In a machine of the character stated, the combination of means for feeding a seamed article into the machine and simultaneously stretching said article, a conveyer mechanism for receiving said article from the feeding means, and means for applying and permanently securing a reinforcing material to said article for covering the seamed portions.

75 6. In a machine of the character stated, a pair of toothed conveyers located adjacent the receiving end of the machine and arranged in diverging relation to feed a seamed article into the machine and simultaneously stretch said article, in combination with means for applying and permanently securing a reinforcing material to said article for covering the seamed portions.

80 7. In a machine of the character stated, a pair of toothed conveyers located adjacent the receiving end of the machine and arranged in diverging relation to feed a seamed article into the machine and simultaneously stretch said article, in combination with a steam supply pipe located adjacent said conveyer and provided with steam discharge outlets normally juxtaposed with respect to the seamed portions of said article, and means for applying and permanently securing a reinforcing material to said article for covering the seamed portions.

85 8. In a machine of the character stated, a pair of toothed conveyers located adjacent the receiving end of the machine and arranged in diverging relation to feed a seamed article into the machine and simultaneously stretch said article, in combination with a steam supply pipe adjustably mounted adjacent said conveyer and provided with steam discharge outlets normally juxtaposed with respect to the seamed portions of said article, means for applying and permanently securing a reinforcing material to said article for covering the seamed 90 portions, and an indicating device for determining the juxtaposed position of said steam outlets with respect to said seamed portions.

9. In a machine of the character stated, the combination of a pair of toothed conveyers located adjacent the receiving end of the machine and arranged in diverging relation to feed a seamed article into the machine and simultaneously stretch said article, a device located adjacent said conveyers for softening the material of the seamed portions, and means for applying and permanently securing a reinforcing material to said article for covering the seamed portions.

10. In a machine of the character stated, the combination of a pair of toothed con-

veyers located adjacent the receiving end of the machine and arranged in diverging relation to feed a seamed article into the machine and simultaneously stretch said article, a device located adjacent said conveyers for softening the material of the seamed portions, means for applying and permanently securing a reinforcing material to said article for covering the seamed portions, and a pressing device adjacent said applying means for pressing the reinforced portions.

11. In a machine of the character stated, the combination of a pair of toothed conveyers located adjacent the receiving end of the machine and arranged in diverging relation to feed a seamed article into the machine and simultaneously stretch said article, a device located adjacent said conveyers for softening the material of the seamed portions, means for applying and permanently securing a reinforcing material to said article for covering the seamed portions, and means adjacent said reinforcing material for alternately pressing and drying said reinforced portion.

12. In a machine of the character stated, a table having an opening therein, means to feed a seamed article across said table with the seam portion passing over said opening, a device located adjacent said opening for applying reinforcing material to said article, a receptacle for adhesive, means operating in conjunction with said receptacle for

removing adhesive and applying the adhesive to one side of said reinforcing material, and means for pressing and drying said reinforcing material after it had been applied to the seam portions of said article.

13. In a machine of the character stated, a table having a plurality of openings therein, a tape-applying device adjacent each opening, means to feed a seamed rug along said table with the seams respectively in alinement with said openings, an indicator for determining the position of the seams, and movable means for shifting said indicator and tape-applying devices whereby the latter is positioned to place the tape over a rug seam.

14. In a machine of the character stated, a table having a plurality of openings therein, means to feed a seamed rug along said table with the seams respectively in alinement with said openings, devices for applying and pressing tapes respectively over said seams, a plurality of receptacles for adhesive mounted for transverse sliding movement, means to coat one side of said tape with adhesive, and an indicator for determining the alined position of said applying devices with the respective rug seams.

In testimony of which invention, I hereunto set my hand.

HENRY E. TERRY.
